TOWEL BAR

Filed Sept. 5, 1928

INVENTOR
VICTOR E. STARNER.
Martin P. Smith
ATTORNEY.

UNITED STATES PATENT OFFICE

VICTOR E. STARNER, OF BELL, CALIFORNIA

TOWEL BAR

Application filed September 5, 1928. Serial No. 304,056.

My invention relates to a towel bar and has for its principal object to generally improve upon the construction of towel bar disclosed in my copending application for 5 United States Letters Patent filed October 5, 1926, Serial Number 139,594.

Further objects of my invention are to provide simple and efficient means for very firmly anchoring the post or base portion 10 of the bar in the wall structure in order to impart to the fixture strength and stability and effectually preventing removal of the fixture unless the entire wall structure is torn away.

15 Further objects of my invention are to provide a towel bar that is capable of being easily and quickly installed for use and the anchoring means for the base or post of the bar being arranged so that no screws or 20 other means of attachment are visible when the bar is properly applied for use, and further to construct the base or post of the bar so that it will readily correspond with the tile utilized on the surface of the wall to 25 which the bar is applied.

Further objects of my invention are to provide a towel bar or rail of the character referred to that is inexpensive of manufacture, enables the towels or wash clothes to 30 be placed upon or removed from the bar by a movement lengthwise of said bar as distinguished from a vertical movement, and, further to provide a towel bar which, when properly constructed and installed presents 35 a neat and finished appearance.

With the foregoing and other objects in view, my invention consists in certain novel features of construction and arrangement of parts that will hereinafter be more fully described and claimed and illustrated in the 40 accompanying drawing, in which:

Fig. 1 is a perspective view of a towel supporting bar constructed in accordance with my invention.

45 Fig. 2 is a horizontal section taken on the line 2—2 of Fig. 1.

Fig. 3 is a cross section taken on the line 3—3 of Fig. 2.

50 Fig. 4 is an enlarged detail section taken on the line 4—4 of Fig. 2.

Fig. 5 is an enlarged cross section taken on the line 5—5 of Fig. 1.

Fig. 6 is a top plan view, partly in section, of a modified form of the means utilized for anchoring the bar in the wall 55 structure.

Fig. 7 is a horizontal section taken lengthwise through the center of a modified form of the bar.

Fig. 8 is an enlarged cross section taken on the line 8—8 of Fig. 7.

Fig. 9 is a horizontal section showing a modified form of the post or base of the bar.

Fig. 10 is a detail section of a modified 65 construction wherein a separately formed rail or bar is detachably connected to the post or base.

Fig. 11 is a plan view of the central portion of a modified form of the towel bar. 70

Referring by numerals to the accompanying drawings and particularly to the form of bar illustrated in Figs. 1 to 5, inclusive, 10 designates a plate preferably formed of metal and said plate being preferably rectangular in form and of such size as to combine readily with the standard sizes of tile that are utilized on the surface of bath rooms, washrooms and the like, and formed integral with and projecting rearwardly 75 from this plate are studs or fingers 11, preferably two in number, and said studs or fingers being provided with longitudinally disposed grooves 12. These studs or fingers are utilized for anchoring the base plate 10 to 80 the wall, and in order to accomplish this result in a firm and substantial manner a horizontally disposed rail 13, preferably of wood, is arranged between and secured to a pair of wall studs S, and formed in the 85 front portion of this rail 13 are bores or recesses 14 of sufficient size to receive the studs or fingers 11.

When the fixture is secured to the wall the 90 bores 14 are filled with a suitable self-hardening plastic material, such as plaster of Paris or magnesite, and the studs or fingers are now inserted in said bores and the excess plastic material will squeeze forwardly 95 through the grooves or channels 12 and when 100

said plastic material becomes hard and set the plate will be very securely anchored to the wall.

In applying the fixture to walls that are provided with tile surfaces the plate 10 lies flush with the tile or takes the place of one or two of the standard sizes of tile.

Formed integral with and projecting forwardly from the center of the plate 10 is a short horizontally disposed post or arm 15, the same being of inverted U-shape in cross section and formed integral with the outer end of this post or arm is a box-like head 16 open at its lower end and the outer faces 15 of the upper and outer walls of this head may be ornamented if desired.

Formed integral with the head 16 and projecting in opposite directions therefrom are inverted channel-shaped rails 17 that occupy the same horizontal plane and said rails are spaced apart a distance of three or four inches from the surface of the wall to which plate 10 is secured.

The ends of the rails 17 are slightly enlarged to form hollow heads 18 which may be ornamented if desired, and these heads are spaced apart from the surface of the wall to which the fixture is secured, thereby enabling towels, wash cloths and the like to be positioned upon or removed from the rails by movements longitudinally relative thereto as distinguished from vertical movements and thus any one towel or cloth may be readily removed without disturbing the other towels or cloths that are suspended upon the rail and therefore there is little tendency of dislodging those towels or cloths that remain on the rail while one cloth or towel is being removed.

While I have shown a fixture having two identical bars 17 projecting in opposite directions from the head 16 to the post or base of the device, it will be understood that in some instances it may be found desirable to dispense with one bar or rail and thus produce a fixture having but one bar or rail that projects horizontally from the base of the fixture.

Formed through the central portion of the plate 10 and beneath the inverted channel-shaped arm 15 is an aperture 19 for the reception of a screw 20, which latter when seated in the central portion of the rail 13 provides additional means for anchoring the fixture to the wall and consequently producing a strong and substantial structure that will support considerable weight (see Fig. 3).

In Fig. 6 I have shown a metal plate or bar 21 that may have its ends secured by means of screws 22 to a pair of the wall studs 11, and which plate or bar carries a pair of rearwardly projecting tubular sockets 23 that are adapted to receive the fingers or studs 11. This plate may be used for anchoring the fixture where it is found impractical to place

a block such as 13 between the wall studs. The plate 21 may take the place of a single lath and when properly set and the tubular members are filled with hardening plastic material the studs 11 on the fixture are inserted in the sockets.

This construction may be utilized where the building is already lathed and ready for the plastering or tile, and under such conditions it would be necessary to remove several laths in order to permit the nailing of a block 13 between a pair of the wall studs. The use of the plate 21 under such conditions will effect a saving of much time and labor.

In Figs. 7 and 8 I have illustrated a fixture wherein the base plate, post and rails are constructed wholly of porcelain or the like and where such structure is employed the inverted channel-shaped rails and post may be reinforced by being filled with self-hardening plastic material such as plaster of Paris or magnesite in which may be imbedded reinforcing members 24 which may be metal rods or wires.

In Fig. 9 I have shown the base plate 10 as being provided on its rear side with integrally formed spaced plates 25 that are adapted to straddle an upright member such as one of the wall studs and said plates being reinforced by integrally formed webs 26. Where this construction is used a screw 27 passes through the plate 10 into the wall stud between the plates 25, thereby very securely and rigidly anchoring the fixture to the wall structure.

In Fig. 10 I have illustrated a construction that may be employed where a supporting rail or bar of extra length is desired, and in this construction the head 16 that is formed on the outer end of the arm 15 is provided with an internally arranged stud 28 that depends from the top plate of said head, said stud being provided with a threaded recess 29. The end of a long rail 30 of wood, glass or metal is positioned within the head 16, said rail being recessed for the reception of the stud 28 and a screw 31 passes upwardly through the end portion of the rail 30 into the threaded aperture 29, thus firmly securing the rail to the supporting arm.

In Fig. 11 I have illustrated a form of bar wherein the base plate 10^a is provided with a single rearwardly projecting pin or post 12^a, and which latter is inserted in an aperture that is formed in one of the wall studs. This form of towel bar may be applied to a wall after the same has been covered with lath and plaster by merely boring a single hole in one of the wall studs for the accommodation of the pin or post 12^a.

Among the especially desirable features of my improved towel bar is the formation of the bar and its base in a single piece, thereby avoiding assembling operations and providing a supporting rail without joints or

seams that would otherwise detract from its appearance. The inverted channel shape of the bar or rail eliminates the necessity for core work in casting and all mechanical work with the exception of the drilling of the screw hole 19 in the base plate is eliminated.

The bar when properly constructed and positioned for use has great strength, presents a neat and finished appearance, cannot be removed without tearing away a considerable portion of the wall, and as the single bar is opened at one end and the double bar open at both ends, towels and the like may be readily removed without danger of accidental displacement of the adjacent towels or wash cloths.

My improved towel bar may be conveniently employed for supporting roller towels.

Owing to the inverted channel shape of the bar or rail it is possible to construct the same of porcelain or the like and to fire the same without warping, which latter operation is accomplished by mounting the bar or rail so that the chamber within same receives and rests upon a form for the full length of the bar. Obviously if the bar were not of inverted channel shape form the same could not be placed on a support for firing.

It will be understood that minor changes in the size, form and construction of the various parts of my improved towel bar may be made and substituted for those herein shown and described without departing from the spirit of my invention, the scope of which is set forth in the appended claims.

I claim as my invention:

1. A towel bar comprising a plate, a short inverted channel-shaped arm formed integral with and projecting outwardly from one side of said plate, an inverted channel-shaped rail formed integral with and projecting laterally in both directions from the outer end of said arm, and there being an aperture formed through said plate within the area surrounded by said channel shaped arm.

2. A towel bar comprising a plate, a short inverted channel-shaped arm formed integral with and projecting outwardly from one side of said plate, an inverted channel-shaped rail formed integral with and projecting laterally in both directions from the outer end of said arm, there being an aperture formed through said plate within the area surrounded by said channel-shaped arm, and a pair of anchoring members formed integral with and projecting rearwardly from said plate to the sides of said aperture.

3. In a towel bar, a plate provided with an aperture, a pair of spaced anchoring members formed integral with and projecting rearwardly from said plate, a short inverted channel-shaped arm projecting forwardly from the central portion of said plate directly above the aperture therein, and an inverted channel shaped rail formed integral

with and projecting laterally in both directions from the forward portion of said arm.

4. In a towel bar, a plate provided with an aperture, a pair of spaced anchoring members formed integral with and projecting rearwardly from said plate, a short inverted channel-shaped arm projecting forwardly from the central portion of said plate directly over the aperture therein, and an inverted channel shaped rail formed integral with and projecting laterally in both directions from the forward portion of said arm, which rail occupies a plane in front of and parallel with said plate.

5. The combination with a wall member in which is formed a recess, of a plate adapted to be positioned on the surface of the wall, a member projecting rearwardly from said plate and occupying the recess in said wall member, a short inverted channel-shaped arm projecting forwardly from said plate, there being an aperture formed through said plate directly beneath said inverted channel shaped arm, and a horizontally disposed rail formed integral with and projecting laterally in both directions from said arm.

6. The combination with a wall member in which is formed a recess, of a plate adapted to be positioned on the surface of the wall, a member projecting rearwardly from said plate and occupying the recess in said wall member, a short inverted channel-shaped arm projecting forwardly from said plate, there being an aperture formed through said plate directly beneath said arm, a horizontally disposed rail formed integral with and projecting laterally in both directions from said arm, and fastening means passing through the aperture in said plate and seated in said wall member.

7. A towel bar comprising a plate, a short inverted channel-shaped arm formed integral with and projecting forwardly from the front face of said plate, there being an aperture formed through said plate between the side walls of said inverted channel shaped arm, an inverted channel-shaped rail formed integral with and projecting laterally in both directions from the outer portion of said arm, and a pair of fluted anchoring members formed integral with and projecting rearwardly from said plate to the side of the aperture therein.

In testimony whereof I affix my signature.

VICTOR E. STARNER.
